UNITED STATES PATENT OFFICE.

JOHN H. McCULLY, OF RUMNEY, NEW HAMPSHIRE.

MACHINE FOR DRESSING AND FORMING LADDER-RAILS.

SPECIFICATION forming part of Letters Patent No. 361,436, dated April 19, 1887.

Application filed December 1, 1886. Serial No. 220,334. (No model.)

To all whom it may concern:

Be it known that I, JOHN H. McCULLY, a citizen of the United States, residing at Rumney, in the county of Grafton and State of New Hampshire, have invented a certain new, useful, and Improved Machine for Dressing and Forming Ladder-Rails, of which the following is a specification.

This invention relates to improved means for planing ladder-rails by power after the same have been properly sawed tapering from end to end, the object of the invention being to leave the surfaces of a ladder-rail more even and regular in form and to do the work more rapidly than if done by hand in the ordinary manner; and it consists in the construction and novel arrangements of parts hereinafter described, and pointed out in the appended claims.

Figure 1 of the accompanying drawings represents a longitudinal central sectional elevation of one of the improved machines. Fig. 2 is a general plan view. Fig. 3 is a sectional elevation of the machine through one set of feed-rolls, enlarged. Fig. 4 shows a front end elevation of the left-hand frame, in which is mounted an arbor carrying one of the cutter-heads for dressing the round side of a ladder-rail, and one of the guide-bars and one side of the machine-bed in cross-section. Fig. 5 shows the rear end of the same and a portion of the bed in cross-section. Fig. 6 represents a cross-section of a ladder-rail as when ready to be passed through the machine, and Fig. 7 a similar view of the same after having passed through. Fig. 8 is an enlarged cross-section taken through the machine-bed and the slide-bars, carrying the upper bearings for the arbors of those cutter-heads designed for rounding the corners of a ladder-rail, showing said arbors, cutter-heads, and lower bearings in elevation. Fig. 9 is an enlarged detail view of one of the adjustable bearings used for the cylinder for planing the flat side of a ladder-rail.

Similar letters indicate corresponding parts.

The bed A is preferably formed of iron, composed of vertical sides and ends and having recesses at various points in the former for receiving the journal-boxes b, carrying the bed-rolls B.

The front end of the machine is at the left in Figs. 1 and 2. Here are placed two guide-rolls, C C, adapted to rotate horizontally upon vertical studs c c, mounted one in either slide D D', placed one forward of the other, and having their ends fitted to and resting within slots formed in the vertical sides of bed A. These rolls may be made to accommodate themselves automatically to the varying widths of ladder-rails by means of a spring, D², either end of which may be attached to the top of the studs c c, which extend high enough for this purpose. Means may also be provided for maintaining these rolls equidistant from the longitudinal center of machine, if desired, by use of a rocker-arm pivoted at its center to a stand supported by the machine-bed A, underneath said slides D D', one end of which may be connected by a short rod to the slide D and the other by a similar rod to the slide D'.

As illustrated by the mechanism used in connection with the sliding bars N, the construction may be the same in both cases, the only difference being that the bars q are in one case pivoted to the bars D D' and in the other to the bars N. One set of feed-rolls, E, should be placed at either end of the machine—those at the front end being fluted, while those at the rear end are left smooth, and preferably covered with some soft yielding material e², so as not to mar the ladder-rail. In order that the upper as well as the lower of these rolls may be moved by power, I extend their journals e on one side of the bed A beyond their journal-boxes, and on them mount bevel-gears F, which mesh with bevel-gears F', carried upon a vertical shaft, f, the lower end of which is mounted in a hanger, f', bolted to the bed A. The upper of the gears F' is fastened rigid to said shaft f, while the lower one is splined thereon, thus permitting a vertical adjustment of the upper feed-roll, E, and the shaft f without interfering with the rotary motion of either roll. These upper rolls, E, and the pressure-rolls E' are all mounted in journal-boxes fitted within a vertical opening, g, formed in either side of the standards G, and suspended by bolts or otherwise from transverse pieces H, which are hung from the top of the said standards by the central rod, H', the lower end of which is rigidly

secured within said piece H, its upper portion passing loosely through the top of the said standard.

The upper feed-roll, E, may be raised or lowered and accommodated to the various sizes of ladder-rails, by turning the hand screws or wheels I, which are threaded to the rod H' and bear upon the top of the standards G. Pressure is applied alike to these upper feed-rolls, E, and the pressure-rolls E' by a spiral spring, h, placed upon the rod H', and compressed between the under side of the top of the standards G and a hand-wheel, I', threaded to the rod H', near the transverse piece H. By this construction the spiral spring h may be compressed or expanded by moving the wheel I' up or down, respectively, and thus increase or decrease the pressure of the upper feed-rolls or of the pressure-rolls upon a ladder-rail while passing through the machine.

Motion is transmitted to the lower feed-rolls, E, which drive the upper ones, by means of the bevel-gears F F', as shown best in Fig. 3, by a spur-gear, K, mounted on the opposite end of either lower feed-roll journal, e, and meshing with a spur-pinion, K', mounted on shaft k, running through or underneath the bed A, and driven by an ordinary belt-pulley, k'.

It may be here mentioned that the bed-rolls are provided with spiral-springs b' upon their journals, which extend a few inches beyond the machine-bed on either side, said springs bearing between their journal-boxes b and collars b'', threaded to the outer ends of said journals, by which the spring-tension may be increased or decreased at will, the purpose of said springs being to allow for lateral movement of said bed-rolls and prevent any unnecessary friction caused by the ladder-rail moving sidewise while passing over said rolls. The journals e', carrying the pressure-rolls E', may also be provided with the springs b' and collars b'' for the same purpose.

A rotary cutter-head, L, is provided, of any suitable form which may be best adapted to carry two or four cutters, l, as in Fig. 2, held at the proper angle to rough off the square corners of a ladder-rail before said rail shall reach the rounding-cutters, to be hereinafter described. This cutter-head L is mounted in bearings formed upon a pressure-plate, L', one of its journals extending far enough beyond said plate and the machine-bed A to carry a flanged belt-pulley, as seen in Fig. 2, by which it is driven.

The pressure-plate L' may be slightly curved upward at either end, especially at the front end, as shown, in order that a ladder-rail may more easily pass under it. At either side a projection, l', is formed, as shown in Fig. 2, which is made a moving fit for the slot g of one of the standards G, said projection having a small shoulder at either side, which bears against the inside of the standards G, as also shown in Fig. 2, a portion of said standard being broken out for this purpose, said plate

L' being adjustably suspended within said standard in the same manner as are the pressure-rolls—viz., by a rod, H', the threaded wheels I I', and spiral spring h.

An ordinary square cutter-head, M, having journals m mounted directly under one of the pressure-rolls and in bearings M', adapted to be vertically adjusted in the machine-bed A by screws m'', as clearly shown in Fig. 9, is provided for planing the flat side of a ladder-rail, (said ladder-rail being put through the machine flat side down,) and is driven by the flanged belt-pulley m', the pulley m' upon the opposite end of the cylinder-journal being used to drive a counter-shaft, which may be located underneath the machine bed A, having pulleys from which a belt may pass to each of the pulleys k', driving the feed-rolls. As the manner of belting the machine is not a feature of this invention, no method is shown.

From the cylinder M the ladder-rail passes between two guide-bars, N, supported near their ends by and adapted to slide upon a transverse piece, n, bolted to either side of the bed. Near the forward end of each of the guide-bars a rod, N', is inserted and rigidly secured. This passes outward through two bearings, O, formed upon a frame, O', bolted to the outside of either side of the machine-bed A in the position shown in Fig. 2.

A collar or wheel, o, is threaded to each of the rods N', outside of the outer bearings, O, for regulating either of the guide-bars N one from the other, as required for different widths of ladder-rails, the distance at which they are set apart being about equal to the width of the narrowest end of a given ladder-rail. Then whether the smallest or biggest end enters the machine first the said guide-bars are caused to move away from or toward each other, respectively, by the passage of said ladder-rail between them and the action of the pressure-springs P, which are placed one upon either of the rods N' and bear between either outer bearing, O, and a tension collar or wheel, o', one of which is threaded to either of the rods N', for the purpose of varying the tension of said springs. Directly under said rods N' a cross-bar, Q, is provided and bolted to either side of the bed, as seen in Fig. 1. To this cross-piece, at a point corresponding with the longitudinal center of the bed A, a rocker-arm, Q', is pivoted, said pivot being placed midway from either end thereof, each of said ends being provided with a connecting-rod, q, extending one to one of the guide-bars N and the other to the other, and pivotally connected thereto for the purpose of causing the said bars N in the movement to and from each other, as previously described, to remain equidistant from the longitudinal center of the bed A.

Two frames, R, located one on either side of the bed A, are provided, each having suitable bearings at their forward end for carrying one of the arbors of the rounding cutter-heads R', their rear ends being pivoted by a rod, r,

to a frame, r' , one of which being bolted to either side of the bed A, as in Fig. 5, and adapted to support said frames R at an angle of forty-five degrees, or thereabout, relative to the vertical sides of the bed A.

The knives or cutters r^2 should be ground so as to cut a quarter-circle, in order that the two cutters R' will suffice to plane the half-round side of a ladder-rail; and that they may do their work perfectly, one should be placed a little back of the other, as in Fig. 2, and thus avoid any liability of contact one with the other.

The frames R may be adjusted, as required, upon the rods r by means of collars r^3 , secured by set-screws to said rods. The forward end of either frame R is supported and made to move up and down in unison with the horizontal movement of the guide-bars N by a roll, n' , carried on the outside of either of the said guide-bars. The said frames R may be provided with a suitable projection, which shall bear vertically against roll n' , as in Fig. 2; or a detachable or adjustable plate, S, may be hung by screws s , threaded to a portion of the said frames, or to the plate S', secured thereto, in the manner shown in Fig. 4—to wit, by turning the thread off from the extreme end of the screws s and forming sockets in the plate S at the proper point to receive this smooth end of said screws. A spring, S², connecting the guide-bar N with an arm, s' , attached to the frame R, insures continuous contact of the plate S and roll n' .

An ordinary flanged belt-pulley may be mounted upon the outer end of these arbors, carrying the cutter-heads R'. After leaving these cutters R' the ladder-rail will have been planed on its flat and half-round side, and all that then remains to complete the work is to remove the two sharp corners. This is easily and perfectly done by two cutters, one operating against each of the said corners of a ladder-rail. These consist of ordinary square cutter-heads T, provided each with two knives or cutters, t , said cutter-heads being each mounted upon and near the upper end of arbors t' .

Journal-boxes U carry the lower ends of said arbors, and these are each pivoted to stands U', secured either to the floor or some higher support, and enable the said arbors to rock in a direction transversely with the machine-bed, so that the cutters may separate or close upon a ladder-rail, as hereinafter described. Belt-pulleys u may be mounted upon said arbors near the journal-boxes U.

The arbors t' pass near their upper end loosely through two slides, V V', placed side by side, one forward of the other, and resting within grooves formed for this purpose in the top of the vertical sides of the machine-bed. These slides carry, respectively, the guide-bars $v v'$.

Just above the cutter-heads T the arbors t' are provided with journal-bearings W W',

pivotedly supported between blocks $w w w' w'$, respectively, by set-screws w^2 , one of which is threaded to each of the blocks $w w w' w'$, and, passing through the same, enter either end of the bearings W W', said blocks being supported and rendered horizontally adjustable upon the guide-bars $v v'$ by means of set-screws threaded to ears $v^2 v^3$, of which there are four, respectively, rising vertically from either of said guide-bars. By this construction the arbors t' may be moved from each other at their top by the movement of a ladder-rail between the cutter-heads T, and also be adjusted relative to the inner surface of the guide-bars $v v'$ for regulating the depth of cut.

A spring, X, may be connected at either end to suitable arms, x , extending perpendicularly from either the upper or lower surface of the guide-bars $v v'$, and hence enable the said guide-bars and cutters to hug close to the sides of ladder-rails of various widths and still return automatically to their normal position after doing their work. It will perhaps be needless to say that the cutters t , in order to round the corners of a ladder-rail, must be ground concave, as shown, and their lower ends be longest.

Having described my invention, what I claim as new, and desire to secure by Letters Patent, is—

1. In power-driven feeding mechanism, the combination, with an arched standard spanning the machine-bed, of an adjustable yoke or frame carrying the upper feed-roll, a rod rigidly fastened thereto and reaching vertically through the bridge of said arched standard, a spring, and means for varying its pressure of said feed-roll upon the work, and a hand-nut threaded to the top of said rod for adjusting said roll to the work, substantially as set forth.

2. The combination, with the bed, of suitable bed-rolls for supporting a ladder-rail, horizontally-adjustable guide-bars separable in a direction transversely with said bed, rotary cutters affixed to arbors mounted in inclined hinged frames located one at either side of said bed, the said hinged frames, a horizontal friction-roll carried upon either of said guide-bars, and an adjustable plate secured to either of said hinged frames and adapted to bear upon said friction-rolls, substantially in the manner and for the purpose set forth.

3. The combination, with automatically-adjustable cutters mounted so as to rotate at an angle of about forty-five degrees, and adapted to plane the half-round side of a ladder-rail, of automatically-adjustable guide-bars connected one with the other by means of a rocker-arm located at the longitudinal center of the machine-bed, either end being pivoted to a rod connecting with one of said guide-bars, and mechanism whereby the movement of said bars outward and inward shall respectively raise or lower said cutter-heads, for the purpose set forth.

4. As a means of rounding the edges of the

flat side of ladder-rails, horizontally-rotative cutters having arbors mounted at their top in adjustable bearings connected to guide-bars, and mechanism whereby said bars are rendered capable of horizontal automatic adjustment by the movement of a ladder-rail between the same, a spring for drawing them toward each other, and means whereby the lower bearings for said arbors are permitted to ac-

commodate themselves to the movement of the upper ones, for the purpose set forth.

In testimony whereof I affix my signature in presence of two witnesses.

JOHN H. McCULLY.
